Primary Examiner — Susan E Krakower*(74) Attorney, Agent, or Firm* — Lee, Hong, Degerman, Kang & Waimey(57) **CLAIM**

The ornamental design for a sporting apparatus, as shown and described.

DESCRIPTION

FIG. 1 is a perspective view of a sporting apparatus; FIG. 2 is a front view of the sporting apparatus shown in FIG. 1;

FIG. 3 is a left side view of the sporting apparatus shown in FIG. 1;

FIG. 4 is a right side view of the sporting apparatus shown in FIG. 1;

FIG. 5 is a rear view of the sporting apparatus shown in FIG. 1;

FIG. 6 is a top view of the sporting apparatus shown in FIG. 1; and,

FIG. 7 is a bottom view of the sporting apparatus shown in FIG. 1.

The broken lines illustrate environmental structure and form no part of the claimed design.
